COTTON TIE BUCKLE

Arthur B. Haswell, Birmingham, Ala.

Application November 23, 1933, Serial No. 699,447

9 Claims. (Cl. 24—23)

This invention relates to bale ties and while not limited thereto it is well suited for baling cotton. The invention aims to provide a simple and inexpensive yet strong and effective bale tie, which will adequately hold a bale of material within predetermined constricted limits. A characteristic feature of the invention relates to the improved buckle having end pieces with inwardly projecting portions adapted to take the first imposed load on a flat surface of the tie strap at a zone other than at the edges of such tie strap. A further feature of the invention is the provision of a buckle having portions so shaped that they will be effective to deform the tie strap in such a way that a tenacious hold will be secured and thus prevent the slipping of the tie relatively to the buckle.

The above and other more detailed aspects of the invention will be fully apparent from the following detailed disclosure when read in connection with the accompanying drawing.

In the drawing—

Fig. 1 is a side view showing a portion of a bale and my improved bale tie holding the same; Fig. 2 is a horizontal section on the line 2—2 of Fig. 1; Fig. 3 is a view similar to Fig. 1, showing the position of the parts prior to the imposition of a load on the strap member of the tie; Fig. 4 is a horizontal section on line 4—4 of Fig. 3; Fig. 5 is an enlarged side view showing the type of bale tie buckle illustrated in Fig. 1 and also showing a portion of the tie strap substantially in the condition it assumes when a load is imposed thereon; Fig. 6 is a horizontal section on line 6—6 of Fig. 5; Figs. 7, 8 and 9 are views similar to Fig. 5 illustrating alternative embodiments of the invention; Fig. 10 is a small scale perspective view of a bale of cotton or other baled material held in constricted condition by a plurality of bale ties embodying my invention.

In the drawing, A represents a body of the baled material such as cotton or the like which is adapted to be held together by a plurality of bale ties indicated as a whole at B. Each bale tie includes a metal strap member C and a buckle member D. The buckle D is preferably formed of a single piece of metal including end members d and side members d'. These connected end and side members define a closed strap-receiving aperture E, through which the free ends c of the strap are adapted to be passed. The transverse width of the aperture E is just a trifle greater in dimension than the transverse width of the strap so that there is sufficient clearance for variation in rolling of the strap.

An important characteristic feature of the invention relates to the provision of means whereby the initial load imposed on the strap will be concentrated at points other than at locations at the outer longitudinal edges of the strap. This is of importance because it is effective to prevent the starting of transverse tears in the strap. The inner edges of the end members d are so formed that they provide inward projections such as indicated at d². These inward projections may take different forms. As illustrated in Figs. 1 to 5 inclusive, the projections are in the form of inwardly curved or crowned portions. Similarly, in Fig. 7, the projections, as indicated at d³, are in the form of inwardly pointed portions. Instead of having merely one inward projection, in some cases, I will provide each member with a plurality of such projections. Such modification is shown in Figs. 8 and 9, the projections in Fig. 8 being rounded, as indicated at d⁴. Or such plurality of projections may be of pointed form, as indicated at d⁵ in Fig. 9.

When cotton and similar material is to be baled with my improved bale tie, it is contemplated that the material will be pressed in a hydraulic or other suitable press and while in such a pressed state the tie strap will be wrapped around the bale and the free ends thereof will be threaded through the strap receiving aperture E of the buckle, as illustrated in Figs. 3 and 4.

In this condition, only a very small or restricted area of the tie strap will contact with the apex of the inward projection of the end member of the buckle. It is thus clear that as the confining pressure on the bale is released the expansive force thereof will tend to tighten the strap about the bale. And because of the peculiar and novel formation of the improved buckle, the first loads imposed on the strap will be transmitted thereto at points on the flat face thereof other than at the edges. This is of importance because it imposes the strain substantially centrally of the width of the tie and inhibits the tendency to tear the strap. As the bulk of the bale continues to expand, the metal of the strap, being of relatively soft and somewhat ductile nature, will be deformed because of its coaction with the inwardly projecting parts of the end piece of the buckle, thus a non-slipping connection between the strap and the buckle is secured. In cases where the buckle is provided with a plurality of inward extensions, such as exemplified at d⁴ and d⁵, the initial load is somewhat divided transversely of the width of the strap. But, regardless of which embodiment

of the invention is employed, the outer longitudinal edges are relieved of strains, thus the tendency to tear or sever the strap transversely is overcome and this advantage is secured even 5 though in applying the buckle the operator may inadvertently skew it to a position other than at right angles to the direction of length of the tie, it being apparent that because of the inward projections, when the load is imposed, the buckle 10 may teeter to a limited extent so as to find its natural position.

This position will of course be determined by the forces acting substantially in the direction of the longitudinal axis of the free ends of the strap. 15 Thus, the buckle with the inward projections described may be said to be self-centering. It is of course understood that the imposition of the full load occasioned by the expansive force of the bale will then deform that portion of the strap 20 in engagement with the buckle and make an effective non-slip joint.

Closed bale tie buckles have heretofore been made and used. But, so far as I am aware they have not been provided with inward projections 25 adapted to take the initial load, nor have they been intended to deform any part of the strap so as to effectively prevent slippage. Thus my improved buckle is an important improvement over the closed bale ties heretofore used. Some of 30 the former types of buckles, in fact, the one most generally used heretofore, is provided with a side opening to permit the strap to be entered by transverse movement. This requires the use of a relatively heavier buckle. Such old buckle, I 35 have observed in practice, weighs approximately .1192 pounds, whereas the buckle of my invention for equal strength will weigh approximately .0522 pounds. Thus with my improved buckle there is a saving of approximately .067 pounds 40 per buckle. When it is considered that some mills produce approximately one million bundles of cotton ties per year, each bundle containing about thirty ties, it will be seen that I effect a saving of about nine hundred gross tons of steel 45 per year by the use of the improved buckle herein disclosed. Thus the buckle itself constitutes an improved article of manufacture having important advantages over the buckles heretofore used for a similar purpose.

50 A further advantage is that the buckle of my invention can be produced cheaper on a roll or in rolling mills than can the buckle of the prior art referred to, which has a side opening.

The above and other inherent characteristic 55 advantageous features of the buckle and bale tie described will be readily apparent to those familiar with the expedients heretofore employed for holding baled material within the confines of a determined compass.

60 While I have described quite specifically the detailed embodiments of the invention herein illustrated it is not to be construed that I am limited thereto and it is intended that the appended claims shall be construed as broadly as 65 is consistent with the prior state of the art.

What I claim is:—

1. A bale tie comprising a metal strap and a

once piece buckle consisting of integral end members and side members defining a closed strap-receiving aperture, each of said end members having a curved inward blunt edged projection effective to initially engage the strap and deform it upon the imposition of a load thereon. 80

2. A bale tie comprising a metal strap and a one piece buckle consisting of integral end members and side members defining a closed strap-receiving aperture, the transverse distance between the inner edges being just a trifle greater than the width of the strap, each of said end members having an inward blunt edged projection effective to initially engage the strap and deform the same without perforating it upon the imposition of a load thereon. 85

90 3. A bale tie comprising a metal strap and a buckle consisting of end members and side members defining a closed strap-receiving aperture, each of said end members having a blunt edged non-piercing inwardly projecting strap deforming portion. 95

100 4. A bale tie comprising a metal strap and a buckle consisting of end members and side members defining a closed strap-receiving aperture, each of said end members having an inwardly extended curved blunt edged strap deforming portion.

105 5. A bale tie comprising a metal strap and a buckle consisting of end members and side members defining a closed strap-receiving aperture, each of said end members having a plurality of blunt edged inwardly projecting strap deforming portions.

110 6. A bale tie including a buckle consisting of end and side members defining a strap-receiving aperture, said end members having inward projections, and a strap the free ends of which are wrapped around the end members and having imperforated deformed areas engaging and substantially conforming to the shape of said inward projections. 115

120 7. A bale tie including a one piece buckle consisting of integral end members and side members defining a closed strap receiving aperture, each of said end members having an inner blunt edged convex strap-engaging edge and a strap whose free ends are wrapped about said end members and having imperforate deformed portions substantially conforming to the shape of 125 said convex edge.

130 8. As an article of manufacture, a bale tie buckle consisting of one piece including connected end and side members defining a closed strap-receiving aperture, each of said end members having an inward non-piercing blunt faced curved projection adapted to initially engage a bale tie strap so as to deform it upon the imposition of a load thereon.

135 9. As an article of manufacture, a one piece bale tie buckle consisting solely of integral end and side members of uniform thickness defining a closed strap receiving aperture, each of said end members having an inner blunt curved face forming a convex strap-deforming portion of the same thickness as said members. 140
